UNITED STATES PATENT OFFICE.

CHARLES F. SCHERENZEL, OF SAN FRANCISCO, CALIFORNIA.

LIFTING-JACK.

1,223,621.

Specification of Letters Patent. Patented Apr. 24, 1917.

Application filed July 24, 1916. Serial No. 110,819.

To all whom it may concern:

Be it known that I, CHARLES F. SCHERENZEL, a subject of the Emperor of Austria, residing at San Francisco, in the county of 5 San Francisco and State of California, have invented certain new and useful Improvements in Lifting-Jacks, of which the following is a specification.

This invention relates to that class of lifting jacks which are actuated through the agency of compressed air.

The object of my invention is to produce an inexpensively and compactly constructed jack which will be rapid and powerful 15 in operation and which is provided with automatically acting devices for regulating the action of the power medium at predetermined elevations of the jack's lifting-bar.

The means whereby these ends are accomplished is described in the following 20 specification and illustrated in the accompanying drawing which shows in transverse vertical section an embodiment of the invention.

25 The reference numeral 1 denotes the frame or standard of the jack which is bored to provide a cylindrical chamber 2 or "cylinder," as it will be hereinafter designated.

Mounted for reciprocatory movements in 30 said cylinder is a piston 3 carrying packing 4. Rigidly secured to said piston is a lifting-bar 5 provided with ratchet teeth 6 for engagement by a pawl 7 which is pivotally mounted on a pin 8 which is supported in 35 lugs, such as 11, provided on the standard.

9 is a relief valve which is yieldingly held against its seat, as shown, to normally close a duct leading from the external atmosphere, and a passage 11 which connects with the 40 bottom of the cylinder 2. Said passage has a branch connection 12 with a detachable flexible tube 13 extending from an air pump or compressed air reservoir.

A spring-closing check valve 14 is provided 45 for the passage 12 and is displaced from its seat 14¹ by the tube coupling 15 when the latter is screwed into the socket therefor in the standard. A spring-pressed detent 16 is provided to engage in a selected 50 one of the notches 17 or 18 of the pawl to releasably hold the same in position to engage the bar-teeth 6, or otherwise.

Adjacent to the upper and lower ends of the lifting bar 5 are provided protuberances 19 and 19¹ extending outside of the 55 plane of the intermediate ratchet teeth 6

for the purpose of influencing the pawl at or near the ends of the bar's travel to effect the reversal of the bar. That is to say, when this bar approaches the end of an upward stroke, the protuberance 19¹ encounters the pawl to swerve the same out of engagement with the ratchet teeth, and cause the arm 20 of the pawl to be swung below the position in which it is indicated by 60 broken lines 20¹ in the view, to engage and push down the valve stem 9¹ to open the valve 9.

When this occurs, the air under pressure escapes from the cylinder and allows the 70 piston 3 and the lifting-bar to descend until the protuberance 19 swerves the pawl into engageable position with respect to the ratchet teeth, and withdraws the pawl from the stem 9¹ when the spring 10 asserts itself 75 to close the valve 9.

If air under sufficient pressure is admitted through the tube 13, the lifting-bar will again be caused to ascend, and so on. The pawl thus serves to influence the valve for 80 the escape of compressed air to the atmosphere, and also serves to support the lifting arm at various elevations should the air supply be interrupted as, for example, when a load is to be sustained for a considerable 85 time.

Besides being controlled automatically to effect the reversal of travel of the lifting-bar at the terminations of its strokes, the bar may be lowered before reaching its 90 highest elevation by the operator pressing the arm 20 downwardly to open valve 9.

The invention is of simple construction, convenient to handle, and may be operated in an inaccessible place by regulating the 95 supply of compressed air either at the source of supply, or by means of a valve provided for the tube 13 at a distance from where the jack is to be employed.

For automobile work, it is peculiarly advantageous by reason of its small size, which enables it to be carried in the machine and by reason of compressed air being usually available.

What I claim is—

1. In a lifting-jack, the combination 105 with a standard having a cylindrical bore, a piston therefor, and a lifting-bar operable with said piston, of means to supply air under pressure into said bore below the 110 piston for effecting the elevation of the lifting-bar, a relief valve, and means en-

2
gageable with and influenced by the bar near the end of its upward travel whereby said valve is caused to open for the escape of the compressed air and enable the lifting-bar to descend to the lower end of its stroke.

2. In a lifting-jack of the class described, a standard, a lifting-bar having a series of teeth, a pawl provided on said standard and adapted to engage the teeth of said bar for releasably supporting the same at various elevations, a relief valve for regulating the pressure of the power medium, and means provided on said bar and engageable with the pawl when the bar approaches the upper end of its stroke whereby the pawl is caused to effect the relief valve for the escape of said power medium and enable the bar to descend.

3. In a lifting-jack of the class described, 20 a standard, a lifting-bar having a series of teeth, a pawl provided on said standard and adapted to engage the teeth of said bar for releasably supporting the same at various elevations, a spring-closing relief valve for 25 regulating the pressure of the power medium, means provided on said bar and engageable with the pawl when the bar approaches the upper end of its stroke whereby the pawl is caused to effect the relief 30 valve for the escape of said power medium and enable the bar to descend, and a second means provided on said bar and operable when the latter reaches the lower end of its stroke to render said relief valve closed and

thereby enable the power medium capable of 35 elevating the lifting-bar.

4. In a lifting-jack of the class described, a standard having a cylindrical bore, a piston operable within said bore, a lifting-bar secured to said piston and provided with a series of teeth, a pawl supported on said standard and engageable with the successive teeth as the lifting rod is elevated, means for effecting said pawl to engage the same with the teeth at the termination of a downward stroke of the bar and means to disengage the pawl from the teeth at the termination of an upward stroke of the bar.

5. In a lifting jack of the class described, a standard having a cylindrical bore, a piston therefor, a lifting - bar operable with said piston, of means to supply fluid under pressure into said bore below the piston to effect the elevation of the lifting-bar, a relief valve for the escape of compressed fluid 55 from said bore, and means influencing said valve and actuated by the alternate strokes of the lifting-bar whereby reciprocatory motion is afforded to the latter through the differences in fluid pressures obtaining under said piston.

Signed at San Francisco, Calif., this 13th day of July, 1916.

CHARLES F. SCHERENZEL.
